(57) **CLAIM**

I claim the ornamental design for a female urination device, as shown and described.

DESCRIPTION

FIG. 1 is a top plan view of the female urination device;
FIG. 2 is a bottom plan view thereof;
FIG. 3 is a side elevation view thereof;
FIG. 4 is a left side elevation view thereof;
FIG. 5 is a right side elevation view thereof; and,
FIG. 6 is a perspective view thereof.
